US00D563022S

(12) **United States Design Patent** (10) **Patent No.:** **US D563,022 S**
Hetfield et al. (45) **Date of Patent:** **** Feb. 26, 2008**

(54) **LUMINAIRE**

(75) Inventors: **Margaret L. Hetfield**, Bristol, RI (US);
James Neeld, Tiverton, RI (US); **Paul Shapiro**, Riverside, RI (US); **Richard Meyer**, Providence, RI (US)

(73) Assignee: **Genlyte Thomas Group, LLC**,
Louisville, KY (US)

(**) Term: **14 Years**

(21) Appl. No.: **29/276,236**

(22) Filed: **Jan. 19, 2007**

(51) **LOC (8) Cl.** **26-05**

(52) **U.S. Cl.** **D26/72; D26/88**

(58) **Field of Classification Search** **D26/72, D26/75, 79, 84, 85, 86, 88, 90, 91; 362/147, 362/404-408, 432**

See application file for complete search history.

(57) **CLAIM**

The ornamental design for a luminaire, as shown and described.

DESCRIPTION

FIG. 1 is an upper perspective view of the luminaire of the present invention;

FIG. 2 is a front view of the design of the present invention;

FIG. 3 is a left side view of the design of the present invention. The right side view is a mirror image of the left side view and is not depicted.

FIG. 4 is a top view of the design of the present invention; and,

FIG. 5 is a bottom view of the design of the present invention.

The broken lines showing environmental structure are for illustrative purposes only and form no part of the claimed design.

1 Claim, 5 Drawing Sheets
